WILLIAM H. WOODS, OF PHILADELPHIA, PENNSYLVANIA.

Letters Patent No. 72,150, dated December 10, 1867; antedated December 6, 1867.

IMPROVED CURTAIN-FIXTURE.

The Schedule referred to in these Letters Patent and making part of the same.

TO ALL WHOM IT MAY CONCERN:

Be it known that I, WILLIAM H. Woods, of Philadelphia, in the county of Philadelphia, and State of Pennsylvania, have invented a new and useful Improvement in Window-Shade Fixtures; and I do hereby declare that the following is a full, clear, and exact description thereof; which will enable others skilled in the art to make and use the same, reference being had to the accompanying drawings, forming part of this specification, in which—

Figure 1 is a longitudinal section, taken in the line x x , fig. 3.

Figure 2, an under-side view.

Figure 3, a top side view.

Similar letters of reference indicate corresponding parts.

This invention relates to an improvement in constructing a fastening for window-shades, and consists in a metal rack, to be attached vertically, as usual, to the side of the window-frame, for holding the cord connected with the shade, by means of a lever-dog that works in a longitudinal slot in the rack, and is engaged and disengaged with the teeth thereof by moving the lever in and out of the slot, to be secured in place when engaged by a swivel knob, on which is a pulley that carries the cord of the shade, as hereinafter described.

A rack has been employed for this purpose previously, as I am aware, but it is not worked by a lever and swivelled knob, but merely by downward pressure of a simple sliding-dog, in a longitudinal slot, that engages in the teeth of the rack by the upward pull of the cord. My improved lever-rack works easily and effectively, and will serve the purpose intended perfectly.

A represents the metal shell or case, to be secured, as usual, to a window-frame in a vertical position. In the upper side of the case is a slot, a a , running from end to end, and on the inner side of the case is a rack, b b , with the teeth pointing downwards, as shown clearly in the drawings. In the slot a is inserted a lever-dog, c , which has a cross-foot, e , at its lower end, to engage in the teeth of the rack when drawn upwards by the cord of the shade to which it is attached. The lower part of the dog c also bends inwards, while the upper part lies flat on the top of the case A , extending upwards. A knob, d , is swivelled in the upper part of the lever-dog c , and its stem or shank passes through the slot a a . On the end of the stem is a cross-bar, g , that holds the lever down flat and close to the case, when it is turned crosswise of the slot, upon the face of the rack, and also engages the cross-foot e in the teeth of the rack at the same time, while it also allows the lever to be raised from the case, and passes out of the slot itself, when it is turned in line with it, and thus disengages the cross-foot e from the rack, and allows the lever to be slipped down easily to tighten the shade-cord that passes over a pulley, s , placed on the stem of the knob d , between it and the lever. A check or stop-pin, n , is placed on the under-side of the lever to check the cross-bar, when it is turned in line with the slot.

The drawings present different views of the rack, when the lever-dog is engaged in its teeth to hold the cord tight, for keeping the window-shade raised to any height; and in fig. 1 the position of the lever is shown in red, when raised, and the cross-foot e is disengaged, for the purpose of raising or lowering the window-shade. For tightening the cord, it is only necessary to bear downwards on the knob d , and then push the cross-bar g into the slot a , and turn it crosswise, to engage the lever-dog cross-foot e , in the rack, and thus secure the window-shade with a tight cord.

Having thus described my invention, what I claim as new, and desire to secure by Letters Patent, is—

The lever-dog c , with the cross-foot e , engaging and disengaging the teeth of the rack b b , in combination with the swivelled knob d , having a cross-bar, g , and working in the slot a a of the rack-case A , substantially as and for the purposes herein described.

The above specification of my invention signed by me, this 28th day of March, 1867.
